UNITED STATES PATENT OFFICE.

ALONZO H. CONKLING, OF VALLEJO, CALIFORNIA.

CHURN.

SPECIFICATION forming part of Letters Patent No. 249,901, dated November 22, 1881.

Application filed July 9, 1881. (No model.)

To all whom it may concern:

Be it known that I, ALONZO H. CONKLING, of Vallejo, Solano county, State of California, have invented a new and Improved Churn, of 5 which the following is a specification.

The object of my invention is to provide an arrangement of machinery and parts of a rotary churn by which it may be operated with more or less power as it may be available, and 10 with or without dashers, and at a slow or fast speed, and by one or two operators at either or both ends of the churn, as desired, thereby making the churn more convenient and serviceable than similar churning not having like arrangements of parts and machinery. 15

In the accompanying drawings, Figure 1 is a longitudinal sectional elevation. Fig. 2 is an end view.

In both figures like letters refer to like parts.

20 A is a box of square transverse section, as long as suitable. This box is supported on flanged trunnions B B', fastened with screws exactly in the center of the exterior of the opposing heads of the box. These trunnions rest 25 in bearings C C', which are fastened on top of two wooden frames, D D'. The trunnions have journals turned upon them a trifle less in diameter than the remainder of the stem, so as to leave a shoulder at each end of the bearing 30 to prevent end-play. The trunnion B has a round hole through it, through which the dasher-shaft E passes. The trunnion B' supports the other end of the dasher-shaft, the shaft entering about an inch into the trunnion. The 35 trunnion B' has a square end projecting through the bearing C' to receive the crank-handle F'.

The crank-handle F is similarly attached to the end of the dasher-shaft which projects through the trunnion B. The dasher-shaft is 40 square between the heads of the box and on one end to receive the crank, but is round where it passes through the trunnion B and where it enters into the trunnion B'; also where the gear-wheel G fits upon it.

45 To prevent the dasher-shaft E from moving endwise, I cut an annular groove in it, which receives the point of the set-screw H, which screws through the trunnion B just outside the bearing C.

50 The dashers I I' are separate. Each set is

formed of four square wooden bars, each an inch less in length than half the distance between the heads of the box. The ends of these bars are secured in radiating wooden arms which have square holes in their centers to 55 fit on the shaft E. To avoid wear of the shaft in these holes I provide iron washers J J, made secure to the arms and fitting snugly on the shaft E.

The bevel-gear wheel G is secured on the 60 shaft E with a set-screw, K, so that it may be easily loosened and thrown out of gear when desired. The gear-wheel G may have, say, fifty teeth. On the head of the box A there is secured the bevel-gear wheel L, say with 65 one hundred teeth.

M is a short counter-shaft, supported in a bracket-bearing, N, bolted to one leg of the frame D. On one end of this counter-shaft there is a bevel-pinion, O, of, say, twenty-five 70 teeth, engaging with the wheel G, and on the other end there is a pinion, P, also having twenty-five teeth, which engages with the wheel L.

The pinion P may be secured to its shaft by 75 a set-screw, so as to be set loose and slipped back when it is desired to disconnect the gearing and throw them entirely out of action. The same effect may be produced by loosening the set-screw in the hub of the gear-wheel G and 80 slipping that wheel back; but if the noise of the running gears is to be entirely stopped, both the wheel G and pinion P must be thrown out of gear. The frame D D' has handles d d'.

The box A has an ordinary cover, Q, with 85 beveled edges. It must be large enough to pass the dashers in and out. It is held firmly in place by a set-screw passed through the center of a cross-bar, R, inserted in staples made fast to the box just beyond the edge of the 90 opening. There should be a vent-hole, S, in the box, so that when necessary the churn may be momentarily stopped to give ventage, as is commonly practiced in such churning.

T is the discharging-hole for the buttermilk 95 after the churning is completed and the butter is taken out.

The operation of my churn is as follows: The box being cleaned and the dashers put in place, the crank-handles F F' are put on and the 100

- gears G and O and L and P engaged with each other. The churn is then filled with milk or cream. Now, if the handle F be revolved, say, fifty times a minute, the dashers will move 5 fifty turns too, and the box twenty-five revolutions in a reverse direction. To attain this speed, however, with a large churn, there will be needed two operators, and by my arrangement one may be located at one end and one 10 at the other. The operator on the dasher-shaft would have the least labor and the other operator perhaps twice as much if each operated separately and independently; but with my combination of gears the power applied is 15 equally distributed from each crank, both to the dashers and the box A, so that the efforts of the operators are equalized as if both turned but one and the same crank, or both cranks were upon one and the same shaft.
- 20 When it is desired to churn without the dashers, they may be taken out entirely, or, if the pinion P be loosened and slipped back, the box alone may be revolved by turning the crank-handle F'. Also, if it is desired to revolve the 25 dashers without revolving the box, the set-screw of the gear-wheel G may be loosened and the wheel slipped back out of gear. The crank F will then revolve the dashers alone without moving any of the gear-wheels.
- 30 The churn may be operated with good effect, first, with dashers and box both revolved by one operator alone, at either end; second, with

dashers and box both revolved by two operators, one at each end; third, with box revolved alone, the dashers being withdrawn, with one 35 or two operators, with the gears thrown in or out; fourth, with dashers revolved alone by one operator; fifth, with gears thrown out and box and dashers revolved by two operators at varying speeds. These differing modes of operating have the advantage of making the churn suitable for operating with milk or cream, and with more or less power, as it may be at hand. The more power applied the quicker the work is done, and vice versa. 40

What I claim as my invention, and desire to secure by Letters Patent, is as follows:

1. In a rotary churn, the combination of box A, shaft E, cranks F F', dashers I I', pinions O P G, shaft M, gear L, and set-screw K, as 50 set forth.

2. A churn-body provided with dashers, in combination with cranks at both ends, and means whereby churn body and dashers can be revolved in opposite directions by one or 55 both cranks, and disconnecting means which permit the dashers to rotate while the churn-body remains stationary or is revolved by the opposite crank.

ALONZO H. CONKLING.
